UNITED STATES PATENT OFFICE.

CHARLES W. T. DAVIES, OF NEW YORK, N. Y.

NECKTIE.

1,171,930.

Specification of Letters Patent. Patented Feb. 15, 1916.

Application filed June 18, 1913. Serial No. 773,913.

To all whom it may concern:

Be it known that I, CHARLES W. T. DAVIES, a subject of the King of Great Britain, residing at New York, county of New York, 5 and State of New York, have invented certain new and useful Improvements in Neckties, of which the following is a specification.

This invention relates to neckties.

10 Heretofore neckties having tying ends have been difficult to slide or adjust on turn-down or double collars due, either to placing the necktie too low down, with resulting tendency to slip downwardly off the collar 15 because too loosely engaged by the outer fold thereof, or by reason of being placed too high, being tightly pinched by the folds of the collar beneath the upper edge thereof. When a necktie is slid one way or the 20 other between the folds of a double collar, in effecting such adjustment as may be necessary to properly position its tying ends, the necktie band has a tendency to ride up the collar and to wedge and bind between the 25 folds of the latter where they join each other. Consequently, whether the ordinary necktie be placed around the collar between its folds before the collar is buttoned to the shirt, or, the collar first engaged with the 30 rear collar button and the outer fold of the collar turned upwardly and backwardly for placing the necktie around the inner collar fold, the wearer is confronted with an insecure disposition of the necktie if it is too 35 low on the collar, or, on the other hand, if placed high, or moderately so, pinching and binding thereof by the collar folds, and very great difficulty is experienced in sliding the necktie to bring the tying ends to the proper 40 position for the formation of the knot or bow.

It has been proposed heretofore to provide the neckband of a necktie with a permanent, removable, or detachable anti-frictional facing to cause it to slide freely when 45 between the collar folds, or, to make the neckband of the necktie unusually flat and narrow. The first expedient entails extra expense and results in greater thickness of 50 the neckband, while the second expedient weakens the necktie, and enhances its tendency to ride.

55 My object is to provide an improved necktie adapted for use on double collars, which will require neither of the foregoing expedients to enable it to be easily slid or ad-

justed at will between the folds of the collar when the latter is buttoned on the shirt and, by reason of the novel shape and construction of its neckband, will be adapted by its 60 coöperation with the rear collar button to assume a position avoiding the lower part of the collar, except at the back thereof, and wholly avoiding the narrow and wedging 65 upper inner space where the folds of the collar join, particularly at the back and sides of the collar where the pinching action on the necktie is the greatest.

In my necktie the neckband is composed 70 of all-fabric parts which diverge from, and converge to, the general intermediate portion thereof, or are constructed so as to be adapted to assume the shape or form in question. The general intermediate parts of the neckband between the rear of the collar 75 and its front, avoid both the lower collar edges and the narrow inner space at the folded upper part of the collar, thus enabling the necktie to be easily slid back and forth at will between the collar folds, the 80 rear collar stud or button serving both as a retainer and a guide for the necktie during its movements.

My invention is provided with a projecting part, point, tab, loop, or the like means, 85 carried by the general intermediate portion of the neck-band of the necktie, whereby its adaptability to be slid around the collar by pulling on its tying ends, may be supplemented, if desired, by pulling on said 90 part, point, tab, or loop.

The invention may be carried out in various ways, only a few forms of which are set forth fully hereinafter and are shown in the accompanying drawings. Such disclosures are, therefore, to be considered as 95 illustrative, rather than restrictive, of the scope of the invention.

In the accompanying drawings: Figure 1 is a rear perspective of a double collar with 100 my necktie applied, parts of the collar being broken away, ready for buttoning onto a shirt; Fig. 2, a rear elevation of a double collar whose upper fold is thrown back, the collar being spread out flat, showing 105 the position assumed by the necktie when in use, dotted lines representing the position of the outer collar fold when down, and the collar being shown as buttoned onto a shirt to illustrate the manner in which 110 the necktie coöperates with the rear collar button; Fig. 3, a side elevation of a double

collar, partly broken away, buttoned at both front and back on a shirt, showing the position of the neckband of the necktie when slid around to one side in the operation of 5 tying; and Figs. 4 to 15, inclusive, detail views showing shapes and constructions which may be employed at the intermediate portion of the necktie neckband.

An ordinary folding or double collar 10 composed of the inner and outer folds 1 and 2 is shown. As usual with all such collars, the outer fold 2 folds along the crease or line 3, thereby forming, between the folds 1 and 2, a very narrow space 4 with converging walls which extend around the collar underneath the upper edge thereof. The higher the collar, the narrower this space and the firmer its binding action on the neckband of a necktie, such binding or 15 pinching action being usually greatest at the rear of the collar and nearly as great at the sides thereof.

Generally, the wearer arranges his necktie in the collar above the rear button-hole 5 with the express purpose either of permitting ready buttoning of the button-hole onto the rear collar button 6, or, to avoid engagement with the collar button after entry 20 thereof in the button-hole 5, according to 30 whether it is intended to insert the necktie in the collar before or after attaching it to the shirt. When the necktie is thus placed, the neckband must necessarily be 35 comparatively high up on the collar, especially at the sides where the neckband commences to flare toward its tying ends, so that a forward pull on the tying ends almost invariably results in at least some portion of the upper edge of the neckband 40 slipping into the space 4, which results in the folds of the collar pinching the neckband and rendering it difficult to slide the necktie around the collar. The more thin, narrow, flat, smooth or generally "anti-frictional" a neckband may be, just so much the more is it liable when pulled forward, 45 to slip or ride upwardly on the collar, before sliding around the collar. On the other hand, should the necktie be placed low down 50 on the collar, it slips off the lower edge of the inner fold thereof and between the shirt neckband and the collar, rendering the collar very uncomfortable and preventing suitable tying and set of the necktie. The 55 natural tendency of the wearer is, therefore, to position the neckband relatively high up between the collar folds.

My invention prevents the necktie from rising into the narrow space 4 and its action is due, first, to the shape or form of the neckband; and, second, to the co-operation of my necktie with the rear collar stud. The construction of my necktie also prevents it from dropping or positioning near 60 or below the lower edge of the collar, ex-

cept at the rear thereof where such positioning is attended with no danger of slipping under the lower edge of the collar.

My necktie has its neckband portion composed of parts 7 and 8 which diverge from, 70 and converge to, its intermediate portion 9. The tying ends of the necktie are shown at 10. The construction of the neckband gives it an angular set and compels it, when placed within a collar in a lax and natural manner, to assume a more or less wide V-shaped position therein, its diverging parts branching upwardly and outwardly, throughout their entire length to avoid the narrow space 4 of the collar, while, at the same time, bearing away from its more roomy and lower edges, and it is thus prevented from slipping out from between the collar folds. At the same time a convenient portion of the neckband lies centrally, at the lower rear edge 85 of the collar, thus affording easy and open entry for the shirt stud or button 6, just above the part 9. The tie will remain in this position, held by the circular binding compression of the collar folds, with both 90 collar and tie mutually adjusted and ready for buttoning onto the shirt.

If the wearer should prefer to insert the necktie after the collar has been buttoned to the shirt, he may turn up the outer fold 2, as shown in Fig. 2, and throw the necktie around the inner fold 1 and in so doing catch it beneath the collar button 6, as shown in Fig. 2. This at once adjusts and retains the neckband in its intended and desired position, both lengthwise and depthwise of the collar. The collar button 6 serves as a guide or bearing for the necktie, the upper edge of the neckband sliding against the shank of the collar button, dipping downward and then rising to resume its self-directed passage along the lines of least resistance.

The neckband may be made of any suitable material, either similar to, or different 110 from, the tying ends 10, and it may be made as an independent member of a necktie to which appropriate tying ends may be connected in any desired manner.

The joint of the parts 7 and 8 may be provided with a downwardly projecting part 9^a. This may naturally result from the form of the necktie or be provided as a tab, loop or other device which affords a convenient finger-hold for grasping the necktie at the back and assisting in the sliding thereof around the collar, should there be any hitch in such adjustment. This point, tab, loop, or similar device may be allowed to project (being covered by the waistcoat) 120 should it not slide obliquely upward so as to be covered by the outer fold of the collar (Fig. 3) due to adjustment of the necktie in forming the knot or bow, or, it may be tucked up out of sight between the collar 125 130

and the shirt. The part 9^a may be integral with or attached to the neckband; in the latter case, it may be of any suitable material or shape.

5 In Figs. 4 and 5 the parts 7^a, 8^a and 7^b, 8^b, are shown at different angles. In Fig. 6, I have shown how the parts 7^c, 8^c may be joined by a rounded or curved intermediate portion 9^b. In Fig. 7, the parts 7^d and 8^d 10 have a straight intermediate connecting part 9^e.

In Fig. 8, the parts 7^e, 8^e are made separate and joined together at 9^d. In Fig. 9, 15 these parts are crossed where they are joined at 9^e, and in Fig. 10, one of the crossed and joined parts is extended to form the tab 9^f.

In Fig. 11, the parts 7^f, 8^f are pivotally connected in any manner at 11 whereby the parts of the neckband may be brought to 20 different angles in relation to each other. Fig. 12 shows a metal ring of any form 12 for pivotally connecting the parts 7^f, 8^f so that they may be brought to desired angular 25 relationship to each other.

25 In Figs. 13 and 14, I have shown two ways in which an angular disposition of the parts 7, 8 may be effected, integrally, in an ordinary straight neckband, by folding the neckband back on itself and securing the folded part to the respective parts 30 7, 8, as shown at 13, Fig. 13, and 14, Fig. 14,

the folded parts being suitably connected by stitching or otherwise.

Fig. 15 shows the form of Fig. 14 with a loop 15 of any material held between the 35 stitched down folds 14.

In the use of the word "continuous" in the claim as referring to the neckband, I have reference to any neckband which is incapable of disconnection or separation, 40 whether composed of permanently connected sections, a single continuous piece of fabric, or, however formed.

Having thus described my invention, what I claim as new and desire to secure by Letters Patent, is:—

A necktie having free tying ends and a continuous neckband which is composed of parts that permanently diverge angularly from a substantially central intermediate 50 portion of said neckband, said neckband being provided in the region of the juncture of said portions with a projecting member adapted for use as a finger hold for manipulating the necktie. 55

In testimony whereof, I hereunto affix my signature in presence of two witnesses.

CHARLES W. T. DAVIES.
